[57] ABSTRACT

The specification discloses novel means for coupling sections of pile and a novel method of driving pile utilizing thin-wall composite pile section. The coupling comprises a thin-wall sleeve with a telescoping thick-wall ring or collar mechanically anchored within the sleeve. Tabs integrally formed in the collar, or the entire collar itself, are expanded within the sleeve to form corresponding anchoring pockets in the sleeve thereby mechanically interlocking the collar and sleeve. The coupling is adapted for use in coupling successive sections of thick-wall tubular pile or in coupling thin-wall tubular composite pile or thick-wall tubular pile. Use of the thin-wall tubular composite pile enables employment of a novel method for driving pile which eliminates the necessity for retaining a succeeding thick-wall tubular pile after the initial one is driven home.

PILE COUPLING AND METHOD OF PILE DRIVING

This invention relates to novel means for mechanically coupling sections of pile. The coupling means also optionally forms part of a composite thin-wall pile, utilizable to drive a preceding thick-wall tubular pile to deeper ground penetration. Use of the composite thin-wall pile enables a novel method for driving pile wherein a part of the composite thin-wall pile performs the dual functions of a mandrel and of pile itself.

In driving steel pile of the tubular type, successive sections are commonly welded together on the job site to hold the sections in alignment as the uppermost end of the initial pile penetrates to below ground level. This welding operation must be carefully performed by skilled operators and considerable expense, as well as loss of time due to the time required for the welding, is thereby incurred.

The conventional method of pile driving requires that the tubular pile be of relatively thick-wall construction in order to withstand, with little or no distortion, the forces resulting from the driving or hammering impacts. Thus, where successive sections of pile are welded together, the entire column of pile comprises thick-wall tubular pile. It would be desirable from a cost and weight standpoint if only the initial pile driven into the ground would be required to be of thick-wall construction for the thin-wall pile is entirely adequate as a casing for receiving concrete, cement or other aggregate. However, thin-wall tubular pile is not capable of withstanding, without distortion, the hammering forces required to drive a thick-wall pile to deeper ground penetration.

In the conventional method of pile driving, transportation of thick-wall tubular pile becomes an item of expense because of the weight of pile involved as well as the fact that the pile cannot be nested, space being required for each individual pile.

It is the purpose of the invention to provide a novel coupling means for tubular pile which avoids the difficulties and disadvantages heretofore experienced and which, at the same time, enables driving a pile by a novel method having certain advantages over present practice.

More particularly, I propose to provide a novel mechanical coupling means for sections of tubular pile, in which a tubular sleeve telescopes over the adjacent end of two pile sections and contains internally thereof a collar expanded in part or in entirety to form interlocking pockets in the sleeve. I further propose to provide a composite thin-wall section, embodying the novel coupling means, wherein a thick-wall section of pile is nested in a thin-wall pile section.

I also propose to provide a novel method for driving pile in which the nested pile of the composite pile section is first used as a mandrel by which to apply hammer blow impacts on the pile in the ground, through the driving collar, and secondly is removed from the composite pile and used as a pile section for initial ground placement.

The invention is described hereinafter in detail in relation to the accompanying drawings wherein:

FIG. 1 is an elevational sectional view, showing fragmentarily, a tubular pile shell of thick gauge metal driven substantially full length into the ground,

FIG. 2 is an elevational sectional view, showing a composite pile telescopically superposed on the pile in

FIG. 1, in readiness for the impact of driving blows on the internally nested pile of thick gauge metal,

FIG. 3 is an elevational sectional view, showing the composite thin-wall pile driven full length into the ground, the nested pile of the thick gauge metal removed therefrom, and aggregate filling the interior of the pile,

FIG. 4 is a cross-sectional view, taken on the line IV—IV of FIG. 2, showing the manner in which the collar and outer thin shell of the composite pile are interlocked,

FIGS. 5, 6 and 7 are views, on enlarged scale, of modified forms of collars which may be substituted for the collar shown in FIGS. 2 and 3,

FIGS. 8 and 9 are fragmental sectional views, showing an additional modified form of collar, respectively, (1) before being interlocked with the outer shell and (2) after being expanded to be interlocked with the outer shell, and,

FIG. 10 is an elevational view, in section, showing a variation of the composite thin shell pile in FIG. 2, which is suited particularly as a coupling device for two sections of hollow tubular pile shell of thick gauge metal.

Referring to FIG. 1, a conventional metallic tubular or pipe pile 10 having a boot plate 11 welded to the bottom end, is shown as driven substantially full length into the ground and leaving a customary top end portion projecting above ground level at 12.

In FIG. 2, there is additionally shown an embodiment of my novel composite thin shell pile 13 as telescopically superposed on the projecting end of the pile 10. The thin shell pile 13 comprises an outer pile shell 14 of thin gauge metal, a metallic drive ring or collar 15 of thick gauge metal telescopically inserted within pile 14 and mechanically interlocked therewith as more fully described hereinafter, and a tubular pile 10', similar to pile 10, nested within thin-wall pile 14, and resting on the collar 15.

Collar 15 is an annulus of relatively short axial length, the wall thickness or gauge of which is at least equal to but which may be greater than that of the tubular piles 10 and 10'. The outer diameter of collar 15 is slightly less than the inner diameter of the thin-wall pile 14 to allow the collar to be slidingly inserted into one end of pile 14 to a position where it is desired to anchor it. The collar 15, as shown, has two diametrically located tabs 16 punched or otherwise partially severed on three sides from the wall of the collar. After the collar is positioned in the pile 14, the pile is placed in a suitable chuck surrounding the collar, and by means of suitable power cylinder means the severed tabs 16 are expanded outwardly, thereby simultaneously outwardly expanding the thin-wall pile 14 and providing, automatically corresponding pockets 17 in the pile in which the tabs 16 are interlockingly anchored.

Variant forms of metallic rings or collars 15a, 15b, 15c shown in FIGS. 5, 6 and 7, respectively, may be provided in substitution for collar 15. Collar 15a has four tabs 16a and collar 15b has eight tabs 16b. Collar 15c illustrates the manner in which tabs 16c may be formed simply by making two parallel slits or saw-cuts axially in the wall from one end thereof.

Though the collar 15c is shown as having four tabs 16c spaced apart approximately 90°, the number and

spacing of the tabs may be altered as desired to provide the desired interlocking strength.

With the composite thin shell pile 13 installed telescopically over the upper projecting end of pile 10 in FIG. 2, the upper end of the nested pile 10' projects slightly above the upper end of outer thin-wall pile 14. It will be seen, therefore, that thick-wall pile 10' and thin-wall pile 14 are of substantially equivalent length and may be readily transported in nested condition together to the job site for use there. In view of the saving of space accomplished by nesting the piles, a considerable saving in transportation expense is accomplished thereby.

Since the pile 10' projects above the outer thin-wall pile 14, the latter sustains no distorting stress due to blows delivered to the upper end of the pile 10' by the hammer of the pile drum, all forces being transmitted from pile 10' via the collar 15 to the upper end of the pile 10. As the pile descends further into the ground with successive hammer blows on pile 10', the composite pile members of course follow pile 10 into the ground. When the top end of the outer thin-wall pile 14 approaches closely to the ground level at 12 as shown in FIG. 3, the pile 10' may be raised telescopically out of the outer thin-wall pile 14 and then utilized as the pile 10 was utilized, namely as the initial ground penetrating pile at another location.

Upon removal of pile 10' from composite pile 13, the outer thin-wall pile 14 remains in the ground connected to pile 10 to form a continuous casing from ground level to the bottom of pile 10 within which concrete, cement or other aggregate fill may then be deposited, as indicated in FIG. 3.

It will thus be seen that by providing a composite pile, the thick-wall pile component of which is used in a dual capacity, transportation space is conserved and transportation expense correspondingly lowered because of the nesting of the thick-wall pile component and the outer thin-wall component.

Referring to FIGS. 8 and 9, a variant form of drive ring or collar 15d is shown. Like the other collars 15, 15a, 15b and 15c, collar 15d initially has an outer diameter which is slightly less than the inner diameter of the outer thin-wall pile 14'. However, as distinct from the other forms, collar 15d does not have any tabs corresponding to tabs 16. When it is desired to anchor collar 15d in pile 14', collar 15d is slidably positioned within pile 14' at the desired location, adjacent one end of pile 14'. Then the assembly is placed in a chuck which surrounds the pile 14' on opposite sides of the collar 15d. The metallic collar 15d in a cold state is then expanded circumferentially by any suitable power means, thereby correspondingly and uniformly expanding the outer thin-wall pile shell 14' circumferentially to a larger diameter. There is thus formed within the enlarged diameter portion of pile 14' a circumferential recess 18 within which the collar 15d is interlocked. As in the previous embodiments, the bottom plate 11" of the nested thick-wall pile 10" rests on the upper end of collar 15d, and collar 15d transmits hammer blows from pile 10" to pile 10 via collar 15d, which is retained in aligned position by the thin-wall outer pile 14'.

Referring to FIG. 10, there is shown an assembly utilizing the novel coupling means solely for the coupling two sections of thick-wall tubular pile 20 together. In this assembly the coupling means comprises an outer metallic sleeve 21 of thin gauge metal and of relatively

short length compared to the length of the pile 14, and a metallic collar 22 illustratively shown as corresponding in form to collar 15a shown in FIG. 5. Alternatively, any of the other forms of collars heretofore described 5 may be employed in lieu of that shown. The sleeve 21 and collar 22 are assembled in the same manner that the previously described collars are assembled in the thin-wall pile 14, namely supporting the sleeve 21 in a chuck and then expanding the tabs 23 to correspondingly expand the sleeve wall to form recesses 24 within which the tabs are locked.

In this case, the coupling means is first placed telescopically over the exposed upper end of the lower pile 20, after it is driven sufficiently into the ground, until the collar 22 rests on the top end of the lower pile. It will be understood that pile 20, like pile 10, has a boot plate (not shown) at the lower end thereof. Then the upper pile 20' is inserted telescopically in the upper end of the sleeve 21 until the lower end of the upper pile 20' rests on the upper end of the collar 22. It will be understood that pile 20' differs from pile 20 in that it does not have a boot plate at the lower end thereof. The upper pile 20' is now ready for application of hammer blows to the top end of the pile to apply a driving force to the lower pile 20 via collar 22. In this instance, 15 of course, the upper pile 20' forms the upper section of the casing, including lower pile 20, into which concrete, cement or other aggregate is subsequently 20 poured.

While specific forms of pile coupling means and the method of use thereof have been shown and described herein, it will be apparent that variations thereof are 25 possible within the scope of the appended claims.

I claim:

1. The method of driving tubular pile of the type having a first section formed of relatively heavy gauge metal and a second section formed of relatively thin gauge metal comprising the steps of:
  - a. driving the first section of pile into the ground until only a portion thereof projects above the ground,
  - b. placing over the projecting end of the first section the lower end of the second section including a heavy gauge collar means mechanically engaged with the lower portion of the second section and disposed in alignment with the upper end of the first section,
  - c. inserting a third pile section comprising heavy gauge piling within the thin-walled section and resting the same upon the collar means with its end projecting above the thin-walled piling
  - d. driving the composite piling including said first and second sections further into the ground by applying hammer blows to the projecting end of the third pile section and thereby transmitting them to the collar means, and
  - e. removing the third pile section when the composite piling is fully driven.
2. The method of driving tubular pile of the type having a first section of relatively heavy gauge metal and a second section of relatively thin gauge metal, comprising the steps of:
  - a. driving the first section of pile into the ground until a small portion only projects above the ground,
  - b. attaching a collar of relatively heavy gauge metal within the second section of pile,

- c. telescopically disposing within the second section of pile a third section of heavy gauge tubular pile of a length to project out of said second section,
- d. telescopically disposing the second section of pile, with the third section of pile therein, over the projecting upper end of the first section of pile until supported thereon by said collar, and
- e. applying hammer blows to the projecting top end of the third section of pile to drive the first and second section of pile further into the ground.

3. The method of driving a tubular pile according to claim 2, further comprising the additional steps of:

- a. removing the third section of pile, and
- b. depositing an aggregate fill into the casing formed by said first and second sections of pile.

4. The method of driving tubular pile according to claim 2, further comprising the additional steps of:

- a. removing the third section of pile, and
- b. utilizing the third section of pile as the first section of pile at another location.

5. Composite pile apparatus comprising a tubular pile shell intended to serve as an extension of a pile driven into the ground, said shell being of light gauge and lacking strength to receive and transmit pile driving hammer blows without distortion, a drive collar positioned concentrically with the pile shell and intermediate its ends, said pile shell and drive collar having distorted sections, the distorted sections of the shell and collar being in juxtaposition and cooperatively engaging to form locking means between the pile shell and the drive collar, an upwardly facing driving surface upon the drive collar, said driving surface being unobstructed by the pile shell above the driving surface and said collar being adapted to rest upon the pile driven into the ground when the pile shell is fitted over said pile whereby a second tubular member having sufficient strength to receive and transmit hammer blows may be telescoped with the upper section of the pile shell and hammer blows delivered to the second tubular member will be transmitted to the drive collar and by it to pile driven into the ground without transmission of forces through the pile shell.

6. Composite pile apparatus comprising an outer tubular pile shell of relatively thin gauge metal, a rigid drive collar positioned concentrically within the pile shell, means mechanically interlocking said collar within said thin gauge tubular pile shell comprising pocket means on said thin gauge tubular pile shell and

tab elements on said collar expanded outwardly into said pocket means, a tubular pile member of relatively heavy gauge metal telescopically disposed within said thin gauge tubular pile shell and serving to transmit driving impacts via said collar to a tubular pile over which said thin gauge tubular pile shell is telescopically disposed, said tubular pile member of heavy gauge metal being adapted to be removed when said outer tubular pile shell of thin gauge metal is driven to appropriate depth in the ground.

7. Pile coupling apparatus comprising a sleeve member of relatively thin gauge metal adapted to be positioned in telescopic relation to the upper exposed end of a driven tubular pile, and a rigid collar of relatively heavy gauge metal concentrically secured to said sleeve member, said collar having tab portions partially severed from the wall thereof which, when displaced out of the contour of the wall of said collar, form pockets in said sleeve with which the tab portions become interlocked, said collar being adapted to seat on the upper exposed end of the driven tubular pile and to sustain the impact of blows whereby the sleeve member is driven coincidentally with the driven pile.

8. Pile coupling apparatus for coupling a tubular pile shell of relatively heavy gauge metal in coaxial superposed relation to a similar tubular pile shell of relatively heavy gauge metal already driven, said coupling apparatus comprising a sleeve member of relatively thin gauge metal disposed in telescopic relation to the upper exposed end of the driven pile shell, and a separately formed collar of relatively heavy gauge metal mechanically interlocked in concentric relation with said sleeve member for supporting said coupling on the upper end of the driven pile shell, the tubular pile shell to be coupled to the driven pile shell being disposed in telescopic relation to said sleeve member and contacting said collar, whereby the impact of blows on the upper end thereof is transmitted via said collar to the already driven pile shell.

9. Pile coupling apparatus according to claim 8, wherein the wall of said sleeve member is formed with an annular recess by deformation of said collar thereinto.

10. Pile coupling apparatus according to claim 8, wherein the wall of said sleeve member is formed with an annular recess internally thereof by expansion of said collar thereinto.
